UNITED STATES PATENT OFFICE

JARED BARTON FLEMING, OF TOWSON, MARYLAND, ASSIGNOR TO THE VAN DORN ELECTRIC TOOL COMPANY, OF TOWSON, MARYLAND, A CORPORATION OF OHIO

DESIGN FOR A CASING FOR A PORTABLE ELECTRIC POLISHER

Application filed March 12, 1932. Serial No. 43,164. Term of patent 7 years.

To all whom it may concern:

Be it known that I, JARED BARTON FLEMING, a citizen of the United States of America, residing at Towson, Baltimore County, Maryland, have invented a new, original, and ornamental Design for a Casing for Portable Electric Polisher, of which the following is a specification, reference being had to the accompanying drawing, forming part thereof.

In the drawing:

Figure 1 is a top plan view of a casing for a portable electric polisher showing my new design.

Figure 2 is a view in perspective looking from the rear quarter.

I claim:

The ornamental design for a casing for a portable electric polisher as shown.

Signed by me at Towson, Baltimore County, Maryland, this 8th day of March, 1932.

JARED BARTON FLEMING.
